[57] **CLAIM**

The ornamental design for a reconfigurable toy plane,
substantially as shown and described.

DESCRIPTION

FIG. 1 as a top plan view of a reconfigurable toy plane
showing my new design;

FIG. 2 is a front elevational view;

FIG. 3 is a bottom plan view;

FIG. 4 is a rear elevational view;

FIG. 5 is a right elevational side view which is a mirror
image of the left elevational side view;

FIG. 6 as another top plan view showing the design of
FIGS. 1 through 6 in a toy robot configuration;

FIG. 7 is a front elevational view;

FIG. 8 is a right elevational side view which is a mirror
image of the left elevational side view;

FIG. 9 is a rear elevational view; and

FIG. 10 is a bottom plan view.

FIG. 1
